Patented Dec. 28, 1926.

UNITED STATES PATENT OFFICE.

SAMUEL W. MAHAFFEY, OF CLEVELAND, OHIO, ASSIGNOR OF ONE-HALF TO WALKER
DE HAVEN LEE, OF EAST CLEVELAND, OHIO.

AUTOMATIC WINDOW FASTENER.

Application filed June 15, 1925. Serial No. 37,228.

The objects of the invention are to provide an automatically acting fastener for window sashes which will fasten both of the sashes in any desired position and while permitting the upper window to be raised and the lower window to fall will prevent either window from being opened until the fastener is released by the operator from the inside of the house.

10 The device operates upon both sashes and may be positioned to permit either window to be opened sufficiently to provide for ventilation but when only one window is open neither window can be thereafter opened 15 any wider from the outside to permit a burglar to enter.

The fastener operates upon both windows so that while the upper window can be raised or the lower one lowered neither window can 20 be opened further. The invention comprises a locking lever pivoted upon the upper bar of the lower window sash and having its outer end engageable with the vertical side of the upper sash, a spring for normally pressing locking edge of the lever into engagement with the vertical side of the upper sash, a base plate upon which the lever is pivoted, and a projecting arm by means of which the lever is released from its engagement.

25 The invention is illustrated in the accompanying drawings, hereinafter more fully described, and specifically pointed out in the claim. In the accompanying drawings, Fig. 1 is a perspective illustrating the action of the locking lever; Fig. 2 is a transverse section of the transverse window bars in the closed position showing the locking lever; Fig. 3 is a detail of the lever; Fig. 4 is a detail of the spring, and Fig. 5 is a detail 30 of the base member.

In these views A represents the lower bar of the upper window, sash B represents the upper bar of the lower window sash. C represents the base plate which is secured to

the upper bar of the lower window sash. 45 D is the spring and E is the locking lever.

The lever E is positioned with its lower or inner end engaging with the socket eyes or loops F, F, and is also provided with the outwardly projecting arm G by means of 50 which it is operated.

A spring secured at its rear end at L upon the base plate, normally presses against the arm G, and forces the locking end E of the lever into engagement with the vertical side 55 of the upper sash.

By depressing this arm the lever can be released and either sash can be removed up or down at will, but when the lever is in the locking position neither sash can be opened 60 any further, although either one can be closed, although both sashes can be removed together to leave an opening at the top or bottom of the window as desired.

The base is preferably provided with forwardly inclined side walls J, J, between which the lever is movable, and which prevent the entrance of dust or objects that might interfere with the action of the lever, and the hinge eyes are spaced apart to permit the passage of the operating arm and spring, and a recess K in the front edge of the base plate also facilitates this action.

Having described the invention what I claim as new and desire to secure by Letters 75 Patent is—

In a device of the character described constructed of sheet metal, a base plate having vertical forwardly inclined side walls, and also provided at its inner edge with spaced 80 hinge eyes and an inclined plate or lever pivoted in said eyes and movable between said walls, and a spring secured at its outer end upon said base plate and extending between said eyes underneath said projecting arm. 85

In testimony whereof, I hereunto set my hand this 28th day of April, 1925.

SAMUEL W. MAHAFFEY.
